UNITED STATES PATENT OFFICE.

CARL C. HARRIS, OF ORANGE, MASSACHUSETTS, ASSIGNOR TO RIVET-O MANUFACTURING COMPANY, A CORPORATION OF MASSACHUSETTS.

PACKAGE.

Application filed March 5, 1921. Serial No. 449,959.

To all whom it may concern:

Be it known that I, CARL C. HARRIS, a citizen of the United States, residing at Orange, in the county of Franklin and State 5 of Massachusetts, have invented a new and useful Package, of which the following is a specification.

This invention relates to a package for use in holding a convenient number of eyelets, 10 paper fasteners, thumb tacks or the like, and providing for dispensing them in a convenient manner.

The principal objects of the invention are to provide a package of the above mentioned type for the purpose of avoiding the difficulties of bulky packages, especially the liability of their being tipped over; to provide means whereby a material saving in time is effected by locating each individual 20 article in such a way that it can be slid out of the holder or package readily and will be located at a definite point and right side up ready to be used; and to provide a package of this kind that can be made of paper, 25 celluloid, or other sheet material in an inexpensive and attractive form.

Further objects and advantages of the invention will appear hereinafter.

Reference is to be had to the accompanying drawings in which

Fig. 1 is a plan of an eyelet package constructed in accordance with this invention;

Fig. 2 is an edge view of the same showing it open and indicating in dotted lines its 35 closed position;

Fig. 3 is an enlarged plan of a portion of the device as indicated in Fig. 1;

Fig. 4 is an edge view of the same, and

Fig. 5 is a transverse sectional view of the 40 package on the line 5—5 of Fig. 1.

I have shown the invention in a simple form in which it involves a main or base member 10, preferably of paper or card-board. However, it can be made of celluloid 45 or other sheet material. It is shown as rectangular in form and as having a series of pairs of longitudinal slits 11. At one or both ends these slits are cut backwardly by angular slits 12 for a purpose that will appear. This provides a longitudinal supporting strip 13 extending all the way along between the two slits 11. This supporting strip 13 is integrally connected with main body 10 at the ends of the slits 11. It will 50 be noticed also that this affords two yielding

side members 14 comprising that part of the card-board or other material located between the two slits 12 on each side of each strip 13. These are integrally connected with the main body 10 at a distance from the slits 11 and are otherwise free therefrom and capable of yielding to permit of the entrance and removal of the eyelets 1, but stiff enough to engage their bottom flanges or heads and hold them in position in the device. 60

At the end of the member 10 it is turned backward at 20 and preferably this backwardly extending overlapping strip 20 is reinforced by a fastening member 21 so as to hold it substantially in the position shown in Fig. 2. On the other end of the member 10 there is a cover 23 integrally connected with the base but bent along a transverse line 24 so that it can be turned over as shown in dotted lines in Fig. 2 under the end of the overlapping strip 20. Thus it covers the eyelets and prevents their accidental displacement. 70

With a construction such as shown it will be seen that a definite number of eyelets can be applied to this card and sold with it in a most convenient manner, that the eyelets will be held with sufficient safety especially on account of the use of the cover, and that they are not likely to become accidentally 80 dislodged. At the same time they are so easily inserted and replaced that the filling can be done by machinery and they can be taken out one at a time by any person without experience or skill, and will always be 85 delivered right side up on the surface of the member 10 between the ends of the slit and the end of the card. Thus they are in position for use at once without the necessity of turning them over and rearranging them. 90 The discharge of one of the eyelets is indicated in dotted lines in Fig. 3.

In this way a very simple and inexpensive sale package is provided and one which can be used by the ultimate consumer in an extremely convenient way and at small expense. The package can be used for other headed articles as, for example, thumb tacks, and is convenient to use as a letter enclosure. 100

Although I have illustrated and described only a single form of the invention, I am aware of the fact that modifications can be made therein by any person skilled in the art without departing from the scope of the invention as expressed in the claims. There- 105 110

fore I do not wish to be limited to all the details of construction herein shown and described, but what I do claim is:—

1. As an article of manufacture, a package comprising a base member of sheet material having a plurality of pairs of longitudinal slits arranged in parallel and spaced relation to each other and extending through the base member and having between them a series of strips depressed below the plane of said base member and connected with the base member and each extending in one continuous piece from one end of said slits to the other for receiving and supporting the heads of a plurality of rows of the articles to be supported which rest on the strips with their shanks projecting up above the base member through the space between the slits and having means for admitting the heads under them and permitting their discharge therefrom longitudinally of the slits.
2. As an article of manufacture, a package comprising a base member having two parallel slits therethrough providing a backing strip between them integrally connected with the base at both ends for receiving a row of headed articles, the base member

having side members located along said slits on opposite sides of the supporting strip and overlapping the circular heads of the articles to hold them in position, said side members being terminated by slits at their ends whereby their edges are free but yieldingly connected with the base member for resting on and holding said heads.

3. As an article of manufacture, a device for the purpose specified comprising a base member having two parallel slits therethrough providing a single strip between them integrally connected with the base member at both ends for receiving a row of headed articles over said strip and under the edges of the base member adjacent to said slits, said base member having slits therethrough connected with the first named slits at their ends and each making an acute angle therewith and extending backwardly adjacent thereto on the outer sides thereof for leaving the edges of the base member near the first named slits free.

In testimony whereof I have hereunto affixed my signature.

CARL C. HARRIS.
